UNITED STATES PATENT OFFICE.

HARRY JACOBS, OF PHILADELPHIA, PENNSYLVANIA.

CAP.

Application filed June 18, 1921. Serial No. 478,471.

To all whom it may concern:

Be it known that I, HARRY JACOBS, a citizen of the United States, residing at Philadelphia, in the county of Philadelphia and State of Pennsylvania, have invented 5 certain new and useful Improvements in Caps, of which the following is a specification.

This invention relates to improvements in 10 caps of the well known type having a flexible head band adapted to conform to the head of the wearer, a stiff vizor extending from the head band and being non-yielding in edgewise directions, and a flexible crown 15 portion extending from the head band and overhanging the vizor.

The invention aims primarily to improve 20 the construction of the vizor and its relation to the head band so as to provide a cushioning effect between the head of the wearer and the edge portion of the stiff vizor adjacent thereto for the ease and comfort of the wearer of the cap when it is in service; and, to this end, the invention consists in the 25 novel construction, combination and arrangement of parts hereinafter described and claimed.

In the accompanying drawings, illustrating 30 the invention.

Figure 1 is a bottom view of a cap embodying my invention.

Figure 2 is a vertical section through the same.

Figure 3 is a top view of the cap.

Figure 4 is a sectional detail, on line 4—4 of Fig. 3, showing one of the fastening devices for connecting the crown of the cap to the vizor.

Figure 5, is a diagrammatic view of the 40 vizor, showing its cut away portion with relation to the line of the head-band.

Referring to the drawings, 2 designates the head band of the cap, 3 the crown portion and 5 the vizor.

The outer portion 6 of the head band 2 45 is formed of the fabric of which the main body of the cap is made, and the inner portion 7 of the head band 2 is formed of leather and constitutes the usual sweat band, the entire head band 2 being flexible and easily conformable to the head of the wearer of the cap.

The crown portion 3 forms a continuation 55 of the fabric forming the outer portion 6 of the head band 2 and it may be constructed in any known or convenient manner.

It is made full and loose and it overhangs the vizor 5, as is common in caps of this well known, general character.

The bottom of the outer portion 6 of the head band 2 is turned inwardly and upwardly, and it and the inner portion 7 of the head band are sewed together by suitable stitches 8. A narrow strip 9 of suitable stiffening material is usually sewed to the upturned bottom of the outer portion 6 of the head band 2 and extends around the same between its outer and inner portions 6 and 7, respectively, to give it slightly added stiffness and stability.

The vizor 5 is formed of upper and lower layers 10 and 11, respectively, of fabric and an interposed layer or member 12 of cardboard or other suitable stiff material which is non-yielding in edgewise directions. The 75 fabric forming the layers 10 and 11 is of the same character as the fabric forming the crown portion 3 and the outer portion 6 of the head band 2; and the vizor 5 is attached to the head band 2 between the points 13 80 and 14 by having edge portions of the upper and lower layers 10 and 11 of fabric inserted between the outer and inner members 6 and 7 of the head band 2 and sewed to the bottom of the outer member 6.

The main body of the vizor 5 or that portion thereof which is occupied by the member 12 is stiff and non-yielding in edgewise directions; and the remaining crescent shaped portion 15 of the vizor 5, between the 90 head band 2 and a line of stitches 16, which is not occupied by the member 12, is relatively soft and yielding, for purposes presently appearing.

The member 12 is held in place by and between the upper and lower layers 10 and 11 of fabric which are sewed together by the line of stitches 16 and by a line of stitches which extends around the free edge portion of the vizor, forming a pocket which 100 is occupied and filled by the member 12.

The layers of fabric 10 and 11 forming the yielding portion 15 of the vizor are sewed together by several lines of stitches which are located between the head band 2 and 105 the line of stitches 16 for rendering the yielding portion 15 more stable.

It will be observed that the line of stitches 16 and the adjacent edge portion of the stiff member 12 curve gently away from and 110 back to the head band 2, providing the crescent-shaped outline for the yielding portion

15 of the vizor 5, and that the side parts of the stiff member 12 or stiff portion of the vizor 5 extend to the head band 2, and that the central part thereof is spaced from the head band, being connected thereto by the interposed yielding portion 15.

It will now be understood that the flexible head band 2 will readily conform to the head of the wearer of the cap entirely around 10 the same without interference from the stiff portion 12 of the vizor 5, because the portion 15 of the vizor 5 will yield toward the stiff portion 12 within the entire crescent-shaped region occupied by the portion 15 15 and thus form a cushion between the head of the wearer and the stiff portion 12 of the vizor, while the cap retains all the advantages of a stiff vizor.

The side parts of the forward portion of 20 the crown 3 are connected to the side parts of the stiff portion 12 of the vizor 5 forwardly of the yielding portion 15 thereof by suitable fastening devices 17, which, as herein illustrated, are snap fasteners of 25 usual and well known construction. This arrangement of the fastening devices 17 relatively to the yielding portion 15 of the vizor holds the crown 3 in symmetrical condition with ease and comfort to the wearer

of the cap when it is in service, due to the 30 fact that the pull of the crown 3 between the back of the cap and the fasteners 17 is cushioned at the forehead of the wearer by the yielding portion 15 of the vizor while holding the crown in place upon the head. 35

I claim as my invention:

1. A cap, comprising a crown portion, a cloth covered vizor including a stiffener, cut to leave an unstiffened yielding crescent-shaped portion at the rear of the vizor, the 40 cloth covering at said unstiffened portion of the vizor being joined by a plurality of spaced rows of stitching extending over said unstiffened portion of the vizor.

2. A cap, comprising a crown, a substantially crescent-shaped cloth covered vizor including a stiffener, having a cut-out portion extending along the edge, inwardly between the horns of the crescent, the cloth covering extending over said cut-out portion and 50 stitched together at such cut-out portion with rows of stitching substantially paralleling the edge of the cut-out portion of the stiffener.

In testimony whereof I affix my signature 55 hereto.

HARRY JACOBS.
